FURNITURE TOP TO FRAME CONNECTIONS

William James Bargen, Waukegan, Ill.

Application April 16, 1951, Serial No. 221,232

1 Claim. (Cl. 311—108)

1

This invention relates to a table construction. An object of this invention is to provide a table construction which includes a top and an improved leg construction.

Another object of this invention is to provide a table which is designed for classrooms or the like and which is so constructed and arranged that, when not in use a series of the tables may be nested together vertically or horizontally, thereby effecting a substantial economy in storage space.

A further object of this invention is to provide in a table connected together pairs of legs with a connecting bar secured between the upper ends of the legs and fixed beneath the top, the connecting bar not only forming additional support for the top, but also bracing the upper ends of the legs.

A further object of this invention is to provide an improved leg assembly for tables wherein a pair of legs is connected together by means of a V-shaped integral member, and a connecting bar is fixed between the divergent ends of the V-shaped member.

A further object of this invention is to provide an improved leg assembly which can be secured beneath a top of any suitable shape.

With the above and other objects in view, my invention consists in the arrangement, combination and details of construction disclosed in the drawings and specification, and then more particularly pointed out in the appended claim.

In the drawings:

Figure 1 is a plan view partly broken away of a table constructed according to an embodiment of this invention;

Figure 2 is a front elevation of a table;

Figure 3 is an end elevation of a table;

Figure 4 is a fragmentary sectional view taken on the line 4—4 of Figure 1;

Figure 5 is a transverse sectional view showing the manner in which a series of these tables may be vertically nested together;

Figure 6 is a fragmentary sectional view taken on the line 6—6 of Figure 1; and

Figure 7 is a side elevation of a series of tables nested together horizontally;

Figure 8 is a top plan view of the nested tables shown diagrammatically in Figure 9; and

Figure 9 is a plan view showing diagrammatically the manner of nesting the tables together vertically.

Referring to the drawings and, first, to Figures 1 to 6, inclusive, the numeral 10 designates generally a table top which in the present instance is of segmental configuration having a convex

5 forward side 11, a concave rear side 12 and radially disposed side edges 13. The top 10 is supported by means of two pairs of connected together leg assemblies, each generally designated by the numeral 14. The leg assembly 14 is formed of a pair of legs 15 and 16 which at their upper ends are provided with inwardly curved extensions 17 and 18, respectively, and the curved extensions 17 and 18 merge into a V-shaped horizontal upper portion 19. The V-shaped member 19 is secured beneath the top 10 by means of fastening members 20 which engage through the inner convergent ends of the V-shaped member 19.

15 A horizontal straight connecting bar 21 is secured as by welding or the like to the convex outer sides of the curved extensions 17 and 18, and the upper side of the connecting bar 21 is in the same plane as the upper side of the V-shaped member 19 and is adapted to be secured to the 20 top 10 by fastening members 22. The connecting bar 21 is disposed closely adjacent the side edges 13 of the top 10, and in the present instance the legs 15 and 16 are disposed in outwardly extended 25 position with respect to the side edges 13 of the top 10 so that a series of these tables may be superposed one upon the other in nested form.

20 A shelf 23 is disposed below the top 10 being parallel therewith, and the shelf 23 is secured to the legs 15 and 16 by means of angle brackets 24 secured by fastening members 25 to the shelf 23 and by fastening members 26 to the legs 18. When the tables are disposed in superposed and 30 nested position the shelf of an upper table will rest on the upper side of a lower table top as shown in Figure 5.

35 It will be understood that where the shelf 23 is omitted the leg assemblies 14 may be set inwardly or outwardly from the side edges 13 of the top and that the top 10 may assume any suitable configuration with which the leg assemblies may be 40 associated.

In Figs. 7 and 8 there is shown the manner in which these tables may be horizontally nested together, whereas in Figure 9 there is shown the manner in which these tables are nested together vertically.

45 These leg assemblies 14 are preferably formed out of tubular metal, and the provision of the connecting bar on the upper portions of the legs and the outer ends of the V-shaped member which is integral with the legs provides a means for rigidly securing the legs together and also provides additional support between the legs and the top.

50 Where the leg units are positioned with the legs

flush with or slightly inwardly from the marginal edges of the top, the tables may be nested together vertically by turning an upper table so that the corners of the top will be positioned between a pair of legs of a lower table.

In the horizontal nesting of the tables which is shown in Figs. 7 and 8 the shelf is omitted and the degree of telescoping of one table relative to another will depend on relative positions of the leg assemblies with respect to the side edges of the tops.

What is claimed is:

In a table having a flat top, supporting means for said top comprising a pair of oppositely extending horizontally disposed V-shaped members 15 engageable beneath the table top, downwardly curved extensions carried by the divergent ends of said members, a pair of downwardly projecting legs integral with said extensions, and a tie bar fixed to the convex outer sides of said extensions and disposed in the horizontal plane of the upper sides of said V-shaped members, said bar projecting laterally beyond said extensions and cooperating with said V-shaped members in

forming a rigid top support while simultaneously holding the upper ends of said legs and said extensions against spreading.

WILLIAM JAMES BARGEN.
